ANTHONY ALBERT AUGUSTUS BYRD, OF LONDON, ENGLAND.

HAND TOOL.

Application filed October 2, 1926, Serial No. 139,151, and in Great Britain December 22, 1925.

This invention relates to a new or improved hand tool to be used for the purpose of straining wire, metal bands and the like, or placing the same in a state of 5 tension and securing the ends of such wire or tape together by twisting.

A tool constructed in accordance with the present invention comprises a lever or bar so formed at one end that it can be used to 10 obtain a purchase against the object to which the wire is to be applied and on which the wire is to be tightened the said end being so shaped as to form a fulcrum of the said lever.

15 Adjacent to the fulcrum end of the lever or bar are provided side flanges or brackets that serve for supporting on a suitable axis a small lever that is provided with a cam or eccentrically shaped end to clamp 20 the ends of the wire between said cam and the base or surface of the lever or bar contained within the said side brackets.

In order to accommodate various sizes or gauges of wire or tape the distance between 25 the aforesaid base and the cam lever must be made adjustable and for this purpose suitable flat plates may be secured in any convenient manner to the aforesaid base so as to increase or decrease the space between 30 the cam lever and the aforesaid flat plate which may be roughened in any suitable way to increase the gripping effect.

Obviously the same effect can be obtained 35 by providing the side flanges or brackets of the lever or bar with slots into which blocks carrying the spindle may be secured by any convenient means said blocks having the bore for the spindle provided near to or remote from the aforesaid clamping or 40 gripping surface of the lever or bar or the block may be provided with a central bore for the spindle and by the interposition of packing strips the position of the axis relatively with the gripping surface adjusted 45 to suit the wire to be strained and twisted.

In order that the invention may be readily understood reference may now be had to the accompanying drawing, wherein similar reference characters relate to like parts in 50 all the figures thereof.

Figure 1 is a perspective view of the tool as applied to straining wire loops that are passed through mould plates as commonly used for monolithic building construction.

55 Figure 2 illustrates the several parts of the tool dissociated from one another.

Figure 3 is another perspective view showing the application of the tool to another purpose.

Figures 4 and 5 are respectively fragmentary elevation and transverse section of a modification in the construction of the tool.

Referring now particularly to Figures 1 and 2 it will be seen that the lever *a* at its 60 front end is provided with the nose or beak *b* and on its upper surface with the side brackets *c* that support the spindle *d* upon which is mounted the clamping lever *e* which when turned down in the position 65 shown in Figure 1 grips the pair of wires *f* that are stretched across the space *g* between the mould plates *h* that are presumed to be set up for the construction of 70 a monolithic wall.

75 It will be understood that for the purpose of inserting the wires *f* between the clamping lever *e* and the gripping surface *i* of the lever *a*, the lever *e* is raised into the position shown in Figure 3 and preferably the front 80 end of the lever *a* somewhat raised as compared with that shown in Figure 1. By firstly lowering the lever *e* the wires are gripped and then the tool is forced into the position shown in Figure 1. Obviously the 85 nose or beak *b* will abut against the flanges of the mould plates *h* and so strain the wires *f* that pass across the space *g*, then by turning the handle *j* of the tool the wire will be 90 uniformly twisted as shown at *k* Figure 3. The gripping lever *e* may be then raised as 95 shown in Figure 3 when the tool can be taken away and the ends of the wires *f* cut off if required.

For the purpose of adjusting the space between the clamping lever *e* and the gripping plate *i* for dealing with various sizes of wire the interposition of one of the exchangeable plates *i* which are of different thickness as seen in Figure 2 is all that is 100 necessary and the said plate can be secured in place by screws as shown or otherwise.

Figure 3 shows the application of the tool for straining the wire and securing vertical and horizontal members of reinforcing rods 105 together as commonly assembled in monolithic structures.

The modification illustrated in Figures 4 and 5 consists in providing the brackets *c* with slots *m* to accommodate blocks *n* 110 which form bearings for the spindle *d* upon which the clamping lever *e* is rotatably

mounted. In this case it will be seen that in order to provide for varying distances between the clamping surface of the lever *e* and the gripping surface of the lever *a* 5 packing strips *i'* are placed beneath the blocks *n* and a cover plate *o* fixed to the bracket *c* which carries the set-screw *p* whereby the bearing blocks *n* are secured firmly in position, otherwise this tool is precisely the same and operates in a similar 10 manner to that described in connection with Figures 1 to 3.

It will be understood that the tool above described can be applied to many purposes, 15 other than the examples aforesaid, for example for securing the wire strands around packing cases and the twisting of such wires together in order to securely bind the packet together and prevent access thereto without 20 bursting or breaking the wire or band used for the purpose.

What I claim is:—

1. A hand tool for gripping, straining and twisting wire comprising in combination a hand lever and a cam lever pivotally mounted thereon, said hand lever being provided 25 with a gripping surface and also with a

nose forming a fulcrum, and means for varying the space between said gripping surface and said cam lever for accommodating various gauges of wire. 30

2. A hand tool for gripping, straining and twisting wire comprising in combination a hand lever and a cam lever pivotally mounted thereon, said hand lever being provided with a gripping surface and also with a nose forming a fulcrum there being provided a plurality of exchangeable plates of different thickness for varying the space between said gripping surface and said cam lever for accommodating various gauges of wire. 35

3. A hand tool comprising in combination, a hand lever provided with a nose forming a fulcrum and a gripping surface 40 above said nose, a pair of brackets adjacent to said nose, a spindle carried by said brackets, a cam lever pivotally mounted on said spindle there being provided a plurality of exchangeable plates of different thickness 45 for varying the space between said gripping surface and said cam lever.

In testimony whereof I affix my signature.

ANTHONY ALBERT AUGUSTUS BYRD.
